UNITED STATES PATENT OFFICE.

MARIA FRANKE, OF BRESLAU, GERMANY.

PIN-HOLDER.

No. 926,478.

Specification of Letters Patent.

Patented June 29, 1909.

Application filed January 6, 1908. Serial No. 409,448.

To all whom it may concern:

Be it known that I, MARIA FRANKE, a subject of the Emperor of Germany, residing at Breslau, in Germany, have invented a certain new and useful Improvement in Pin-Holders, of which the following is a specification.

This invention relates to a pin-holder adapted to be attached to an article of wearing apparel and so constructed that pins can easily be removed therefrom without risk of pricking the user's fingers, and that pins which have been used can easily be placed in a box or receptacle forming part of the device.

The invention is illustrated in the annexed drawing, in which—

Figure 1 is a front-view of the device, Fig. 2 a section on the line A—A of Fig. 3, Fig. 3 a top-plan view, and Fig. 4 is a horizontal section of the front of the box on a larger scale.

Referring to the drawing, *a* is a box to the rear-wall *a*¹ of which is fixed a hook *b*, safety-pin or the like. The box has an aperture *c* at the top, and the front-wall thereof is of convex outline, stepped, and forwardly inclined from the bottom to the top. Across the rising portion *a*³ of each step is stretched an india-rubber band *d* or the like, so that pins can be inserted, head upward, between this band and the wall, there being as many rows of pins as there are steps. The pins thus carried can be separately withdrawn for use. The curvature of the wall causes the india-rubber bands to press firmly against the pins, to hold them in their upright positions. To further increase the stability of

the pins the surfaces covered by the india-rubber bands may be grooved to engage them as shown at *a*² Fig. 4.

The device is preferably fastened to the front of the user's dress by means of the hook *b*, in a position which can easily be reached by hand. Pins which have been used are dropped through the aperture *c* into the box *a*. An inwardly bent tongue or flange *e* prevents the pins from falling out of the box when the body is forwardly inclined. The device can also be used for holding small nails and the like in the same manner.

What I claim as my invention and desire to secure by Letters Patent of the United States is:—

1. A pin holder comprising in combination a box the front-wall of which is stepped and made convex, said box having an aperture at the top, means of attachment on the back of the box, and bands stretched across the convex faces adapted to retain rows of pins inserted head upward between the wall and band.

2. A pin holder comprising in combination a box the front-wall of which is stepped and made convex with vertical recesses *a*² therein, said box having an aperture at the top, means of attachment on the back of the box, and bands stretched across the convex faces adapted to retain rows of pins inserted head upward between the wall and band.

In witness whereof I have signed this specification in the presence of two witnesses.

MARIA FRANKE.
